UNITED STATES PATENT OFFICE.

GEORGE F. KNOLLMANN, OF EVANSVILLE, INDIANA.

HEATING DEVICE FOR AUTOMOBILES.

1,057,485.

Specification of Letters Patent.

Patented Apr. 1, 1913.

Application filed June 6, 1912. Serial No. 702,136.

To all whom it may concern:

Be it known that I, GEORGE F. KNOLLMANN, a citizen of the United States, residing at Evansville, in the county of Vanderburgh and State of Indiana, have invented certain new and useful Improvements in Heating Devices for Automobiles; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates broadly to the class of heating devices for automobiles and further contemplates the provision of a device of this character which is simple in construction, strong, durable and efficient in operation and one which can be manufactured and placed upon the market at a minimum cost.

By using the exhaust gases from the engine as a heating medium it is apparent that the cost of operation of the device reduces it to a minimum and that its provision upon a vehicle will not cost any great expense to the owner thereof. It will also be apparent from the hereinafter appearing description that my device will serve the subsidiary function of a muffler, it receiving directly the exhaust gases from the engine's cylinders.

While I have designated in the drawings suitable exhaust gas passages and suitable water passages, it is to be realized that water may be introduced through the gas passages and the gases through the water passages if such occasion presented itself.

With the above and other objects in view my invention consists in such details of construction and in the arrangement and combination of parts as will be hereinafter more fully described and specifically pointed out in the appended claim.

In describing my invention in detail reference will be had to the accompanying drawings wherein like characters denote like or corresponding parts throughout the several views, and in which:-

Figure 1 is a perspective view of my invention. Fig. 2 is a sectional view on line 2-2 of Fig. 3, and Fig. 3 is a sectional view on line 3-3 of Fig. 2.

Reference now being had to the details of

the drawings by letter 14 and 15 designate respectively inner and outer concentrically arranged cylinders spaced apart from each other and intermediate the same are lugs 16. 60 Each end of the outer cylinder is provided with an opening, one being an inlet opening through which a pipe 20 passes and the other an outlet opening from which an exit pipe 25 leads. Said outer cylinder is provided with a circumferential covering 15' of insulating material, and about the latter is a covering of metal 15*. The inner cylinder 14 is provided with a transverse partition 18 near one end so as to form a chamber 18'. Said partition is perforated for the reception of the open ended flues 19, which at their opposite ends are mounted in perforations in one end of the inner cylinder. A partition 22 is mounted within the outer cylinder in the space intermediate the end of the inner cylinder and the exit end of the outer cylinder and is provided with a central aperture 21. A baffle plate 23 is held by means of lugs 24 a slight distance from the exit end of the cylinder 15. An open ended tube 13 passes through openings in the adjacent ends of the inner and outer cylinders, as shown in Figs. 1 and 2 of the drawings. It will be noted that the ends of the tubes 13 are open and are adapted to receive exhaust gases which are conducted through the pipe 20 to the chamber 18' formed intermediate the perforated partition engaged by said pipes 19, and the adjacent end of the inner drum. A pipe 39 passes through the wall of the outer cylinder and communicates with the interior of the inner drum. Water, which is preferably driven by a pump, is forced through the pipe 13 into the interior of the shell 14 and becomes heated by contact with the flues 19 and makes exit through the pipe 39 leading from the upper portion of the shell 14 and through the wall of the shell 15. 95

The hot water, after passing from the shell 14, passes through pipe 19 by the valve 40, pipes 38, 33, 34 and 35, thence by the union 37 and the pipe 36, thence through the union 37 and pipes 33, 34 and 35, through the elbow 32 and pipe 28, through the valve chamber 30, regulated by the valve 29, thence to the connection 27 and through the pipe 26 back to the pump, thus making a complete circuit. The gases, after giving off heat by radiation, make exit through the passageway 25 to the atmosphere. A fun-

nel 29 communicates with the valve chamber 30', regulated by the valve 29'. The valve 29 serves to regulate the flow of water through the pipe 28 and a suitable faucet 5 31 is fitted to the pipe 28 through which water may be drawn from the latter. A pump 12 is mounted upon the shaft 7 in suitable bearings 5 upon the depending bars 3 which are fastened to the frame 1 and a 0 gear wheel 12', driven by a gear wheel 11 fixed to the shaft 6 upon the hanger 3', fastened to the frame. The shaft 6 has a bevelled wheel 10 in mesh with the gear wheel 9 upon the shaft 8, whereby power is supplied to operate the pump.

What I claim to be new is:—

In combination with an outer and an inner cylinder, lugs intermediate the cylinders and spacing the same apart, an apertured 0 partition in the inner cylinder, a pipe passing through the aperture in said parti-

tion and through one end of both the inner and the outer cylinders, a series of open-ended flues positioned within the inner cylinder and extending through apertures 25 formed in one end of the latter and the partition therein, a partition within the outer cylinder having a central opening, a baffle plate within the outer cylinder adjacent to its end spaced apart therefrom, an exit pipe 30 leading from the end of the cylinder adjacent to the baffle plate, and an inlet pipe and an outlet pipe, each communicating with the inner cylinder, as shown and described.

In testimony whereof I hereunto affix my signature in the presence of two witnesses.

GEORGE F. KNOLLMANN.
